UNITED STATES PATENT OFFICE

JAMES CONTESSA, OF NEW YORK, N. Y., ASSIGNOR TO E. BEHRMAN, INC., OF NEW YORK,
N. Y., A FIRM

DESIGN FOR LEATHER OR SIMILAR ARTICLE

Application filed March 12, 1930. Serial No. 34,831. Term of patent 3½ years.

To all whom it may concern:

Be it known that I, JAMES CONTESSA, a citizen of the United States, residing at New York, in the county of New York, State of New York, have invented a new, original, and ornamental Design for Leather or Similar Article, of which the following is a specification, reference being made to the accompanying drawing, forming a part thereof.

The drawing shows a piece of leather or similar article embodying the design, comprising a fanciful grouping of starfish, the dot and dash lines enclosing an area which is a repeat unit of the design.

I claim:

The ornamental design for leather or similar article, as shown and described.

JAMES CONTESSA.
